UNITED STATES PATENT OFFICE.

CLARENCE S. SNAVELY, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

LIGHT-SIGNAL.

1,329,639.

Specification of Letters Patent.

Patented Feb. 3, 1920.

Application filed November 19, 1915. Serial No. 62,341.

To all whom it may concern:

Be it known that I, CLARENCE S. SNAVELY, a citizen of the United States, residing at Edgewood borough, in the county of Allegheny and State of Pennsylvania, have invented certain new and useful Improvements in Light-Signals, of which the following is a specification.

My invention relates to the adjustment of incandescent electric lamps so that the filament of the lamp will occupy a predetermined position with relation to the lamp bulb.

Incandescent lamps which have been adjusted in accordance with my invention are particularly adapted for use in apparatus comprising a lamp and an optical device—such as a reflector or a lens or both—for projecting a beam of light from the lamp; such apparatus may, for example, be a light signal for use in railway signaling. In apparatus of this type it is desirable to employ what is known as "concentrated filament" lamps; that is, lamps whose filaments are concentrated as nearly as possible at a point. In order to obtain the highest efficiency, it is necessary that the filament be located at a definite point with relation to the reflector or lens, this point usually being the focus. In the manufacture of these lamps, however, it has been found difficult to locate the filament accurately in a predetermined position with relation to the bulb, so that this position varies with different commercial lamps, hence even if the bulbs are all mounted in the same position in the signal the filaments of the several lamps will vary in position with respect to the reflector or lens.

My invention, therefore, provides for adjusting the parts of a commercial lamp so that the filament will occupy a predetermined position with respect to the lamp bulb; means can then be provided in the signal for mounting the lamp so that the bulb occupies a predetermined position with respect to the reflector or lens, this position being such that the filament will occupy the desired position with relation to the optical device or devices of the signal. When the lamp is replaced by another properly adjusted lamp, the filament of the new lamp will, of course, occupy the proper position

with respect to the optical device or devices, so that no adjustment is required in the signal itself.

In the accompanying drawings, Figure 1 is a view showing one form of apparatus for adjusting the filament of a lamp with respect to the bulb and embodying my invention. Fig. 2 is a plan view of member 7 shown in Fig. 1. Fig. 3 is a view showing one type of standard adapted for use with the apparatus shown in Fig. 1. Figs. 4 and 5 are views showing one form of pliers for bending the neck of the bulb of lamp L. Fig. 6 is a view showing one form of base for the lamp bulb. Figs. 7 and 8 are views showing one form of apparatus embodying my invention for locating the lamp bulb with respect to a lens. Fig. 9 is a view showing a modification of the apparatus shown in Figs. 7 and 8. Fig. 10 is a plan view showing a modification of the apparatus shown in Fig. 1. Fig. 11 is a view showing in vertical section the apparatus shown in Fig. 10. Figs. 12 and 13 are views, showing diagrammatically another modification of the method embodying my invention or locating the filament at a predetermined position within the lamp bulb.

Similar reference characters refer to similar parts in each of the several views.

With reference to Fig. 1, the letter A designates a base plate on which is fastened by screws 1 a C-shaped supporting frame 2. Reference character K designates a clamp for grasping the bulb 4 of an electric incandescent lamp L. Clamp K comprises an upper member 5 having a central hole 6 to receive the upper part of bulb 4, and a lower member (see also Fig. 2) which as here shown is a plate 7 having a central hole 8 to receive the lower part of the bulb. Two pins 9 are inserted into the lower face of member 5 and are threaded at their ends to receive nuts 10. Fins 9 are adapted to enter slots 11 in plate 7, so that, when nuts 10 are drawn up, the plate clamps the lamp bulb firmly against the upper member 5. It is apparent that clamp K is very simple to manipulate. A simple counter-clockwise twist allows lamp L to be removed from the clamp and conversely a clockwise twist clamps the lamp in place. The firmness of

the grip of the clamp can easily be adjusted by nuts 10. Clamp K is mounted on member 2 by means of a stud 3 which extends upwardly from the center of member 5 through a hole in frame 2. A head 12 is fixed to the upper end of the stud by a pin 13, so that the clamp depends from frame 2 and is free to turn about its vertical axis $a-b$. However, for purposes which will 10 appear hereinafter, it is desirable to limit the angular motion of clamp K to approximately a right angle. This may be done by any suitable means such, for instance, as pegs 35 screwed into the upper member 5 of clamp K approximately 90° apart (only one of these pegs appears on the drawing). The pegs are adapted to engage a stud 36 secured in frame 2, so that the motion of clamp K is limited to the angle between 15 pegs 35.

Reference character T designates a telescope, one end of which extends through a hole in frame 2 and rests in a circular opening in a plate 14 screwed to the vertical portion of frame 2, and the other end of which is mounted by adjusting screws 15 in the ring-shaped end of an arm 16 riveted in frame 2.

Reference character B denotes a blow pipe 30 whose vertical tube 17 is adjusted to a sliding fit in a sleeve 18 extending through the lower horizontal portion of member 2 and base A. The lower end of tube 17 is adapted to receive gas and air from flexible tubes 35 26 and 27. The upper end of tube 17 has a shoulder 19 over which fits a hollow pulley 20. A collar 21 engages the lower edge of shoulder 19 and is screwed to pulley 20 so that the pulley is prevented from slipping 40 off the top of the tube. Pulley 20 is provided with a tubular extension 24 closed at its upper end. Two diametrically opposite arms 22 and 23 branch out from extension 24 and terminate in tips 25. The mixture 45 of gas and air flowing through tube 17 forms into two jets, one from each tip 25. If the pulley is revolved by suitable means not shown, these jets are set into rotation and, when ignited, apply an even heat to 50 an object inserted between them. The blow pipe normally slides downward by gravity until collar 21 is seated on the upper flange of sleeve 18. When the blow pipe is raised to the position shown in the drawing, the 55 flames impinge on the neck of bulb 4, so that the glass is readily heated to a ductile state.

The use of the apparatus as thus far described may be explained as follows. The 60 operator inserts a "standard" S into member 5 of clamp K as shown in Fig. 3. He then adjusts the telescope until its cross hairs cover the ball tip 30 of a stud extending downwardly from the center of standard S. The operator then removes the

standard but leaves the telescope in the adjusted position. It may be noted that the telescope is now so directed that its line of sight intersects the vertical axis $a-b$ of clamp K at a fixed distance below member 70 5 of the clamp. The operator then fastens a lamp L in the clamp and proceeds to heat the neck of the lamp bulb by raising the blow pipe to the position shown in the drawing. After the rapidly rotating flame of 75 the blow pipe has heated the neck of the bulb to an even red heat, the operator brings the filament into the intersection of the cross hairs by bending the neck of the bulb by a suitable tool, such for instance, as I 80 have shown in Figs. 4 and 5. This tool is a pair of pliers having slender jaws 33 bent at right angles to the handle portion. The operator inserts the tips of these jaws into the hollow stem 32 on which the filament is 85 mounted (Fig. 1) and by pressure on the handles causes the jaws to open and press outwardly against the walls of stem 32 so that the stem is forced to follow the movement of the plier tips. The operator turns 90 clamp K until one of the pegs 35 engages stud 36, sights through the telescope and brings the filament into the intersection of the cross hairs by proper manipulation of the pliers. He then turns clamp K through 95 an approximate right angle, *i. e.*, until the other peg 35 engages stud 36, and repeats the operation.

In the above-described manner the operator has brought the filament into the same 100 position relative to member 5 of clamp K as the ball tip 30 of the standard S occupied when it was inserted into the clamp K for adjustment of the position of the telescope. This is also true of the filament of every 105 lamp subsequently adjusted. It follows that the filaments of all the lamps adjusted in this manner occupy the same pre-determined position with respect to the bulb surface.

The lamp bulbs are next provided with 110 a base, for example, such as I have shown in Fig. 6. Reference character 40 designates a shell of insulating material having a central prong 41, the tip of which is inserted into the hollow stem 32. The lead-in wires 115 which pass through stem 32 are connected to metallic studs 43 whose heads are fastened in shell 40 and whose shanks extend outwardly from the shell as shown. The base is fixed to the lamp bulb by a suitable 120 cement 45.

In Figs. 7 and 8 I have shown the lamp placed into proper position with respect to a pair of Fresnel lenses. Reference characters 46 denote a pair of springs attached by 125 means of screws 48 and terminal posts 49 to a rigid supporting member 47 of insulating material. Member 47 and the Fresnel lenses are mounted in a casing which I have not shown on the drawing, so that they are 130

immovable with respect to each other. The ends of the springs are bent to form semi-circular recesses 50. A cross bar 51 of insulating material is riveted at its ends to 5 springs 46 and is provided at its middle with a stud 52 whereby the springs may be conveniently bent. The lamp is inserted by the simple process of placing the upper end of the bulb into a corresponding recess in 10 the Fresnel lens, pulling the springs backward by stud 52 and slipping the studs 43 into the recesses 50. The pressure of springs 46 not only holds the lamp in place with respect to the lens, but also causes a firm 15 contact between springs 46 and studs 43 so that the circuit is completed from one terminal post through the lamp filament to the other terminal post.

As indicated in Fig. 7 the lamp filament is 20 at the focal point of the Fresnel lens combination. This is made possible without adjusting the lamp relative to the lenses because, as described hereinbefore, the filament is at a definite position in the lamp bulb, 25 which position is such that the filament occupies the focal point as shown when the lamp bulb is clamped in position. Naturally the filament of any lamp bulb similar in size and shape and similarly adjusted will occupy the focal point when substituted for 30 the first lamp.

Sometimes the focal distance of the lens is so long that the lamp bulb would have to be excessively large in order to be located by a 35 recess in the lens proper. In that case I provide a casting comprising a ring 55 for receiving one end of the lamp bulb as shown in Fig. 9. Three spider arms 56 lead from ring 55 to another ring 57 which is adapted 40 to receive the lens. In this manner the lens and the lamp are both fixed with respect to the casting, so that the lamp and the lens are also fixed with respect to each other. The distance between rings 55 and 57 is such 45 that the filament of the lamp occupies the focal point of the lens, or any other desired point with respect thereto, when the lamp is placed into the position shown on the drawing.

50 It should be noted here that it is not essential that all the signal lamps have bulbs of exactly equal size and shape, provided that the clamp which secures the lamp in the signal is similar to the clamp which secures 55 the lamp in the adjusting stand. By this I mean that for dissimilar lamp bulbs the surface *a* of ring 55 (Fig. 9) against which the bulb rests in the signal must be exactly the same as the surface *b* of member 6 of clamp 60 K (Fig. 1) against which the bulb is clamped while the filament is being adjusted. For, no matter what the size or shape of the bulb, the filament after adjustment is at a definite predetermined position with respect 65 to the surface *b* of clamp K, and it will be

at the same relative position to surface *a* of ring 55 when the lamp is clamped to the ring. Of course, care must be taken that the same portion of the surface of bulb L which was in contact with surface *b* of clamp K 70 while the lamp was being adjusted is brought into contact also with surface *a* of ring 55 when the lamp is inserted in the signal. This means, simply that if the lamp bulb is located in clamp K with its axis perpendicular to the plane of surface *b*, the bulb 75 must be clamped in the signal with its axis perpendicular to the plane of surface *a* of ring 55—as shown on the drawing.

Instead of a telescope other optical devices may be used for locating the filament in a definite position with respect to the lamp bulb. In Figs. 10 and 11 I have shown, for example, a clamp K' (similar to the clamp K shown in Fig. 1) provided with 80 two so-called sights T¹ and T² of the following construction. As shown in Fig. 11, sight T¹ comprises a vertical supporting member 60 fastened at its upper end to clamp K' by screw 61 and bent at right angles at its lower end to support an inclosing 85 casing 62. Inside casing 62 is a mirror 63 at an angle of 45 degrees to the vertical and a lens 64 adapted to receive light entering the casing through a hole in member 60. 90 The upper face of the casing 62 comprises a plate of ground glass 65. As shown in Fig. 11, rays of light from lamp filament 31 pass through lens 64, are reflected from mirror 63, and are focused on the ground glass 100 screen 65, where they form an image of the filament (as shown in dotted lines in Fig. 10). Sight T² is of similar construction to sight T¹ and therefore also forms an image of the filament, but, being at right angles to sight T¹, this image is at right angles to the image in sight T¹. The center of each sight T¹ and T² is determined by cross hairs on the ground glass 65 and the sights are so 105 adjusted before they are fixed to clamp K' 110 that they definitely locate a point on the vertical axis of clamp K' at a predetermined distance below its upper member 5'. In the use of this apparatus, the operator fastens the lamp bulb 4 in the clamp similarly as 115 described for Fig. 1 and heats the neck of the lamp by suitable means as hereinbefore described. He then inserts the jaws of the pliers shown in Figs. 4 and 5 into the stem 32 and bends the neck of the lamp bulb until 120 the filament is in the desired position as is indicated by the position of the images of the filament with respect to the cross hairs of both sights T¹ and T², as shown in Fig. 10. Since the operator is able to watch 125 both sights T¹ and T² simultaneously, this method of adjustment is more expedient than the method described in connection with Fig. 1.

Still another way of securing an accurate 130

adjustment of the lamp filament with respect to the lamp bulb is shown in Figs. 12 and 13. In this method I make use of the so-called reflex image of a lamp filament in a spherical or elliptical lamp bulb. The spherical lamp bulb acts as a reflector of the filament within the bulb and produces an image of the filament as far to one side of the center of the bulb as the filament is 5 placed from the opposite side of the center, as I have indicated diagrammatically in Fig. 12. The reflex image of the filament is barely visible when the filament is cold but is distinctly noticeable when the filament 10 is heated to a dull red. For use of the reflex image of the filament for adjusting the filament with respect to the bulb the operator connects the lead-in wires of the filament to a source of potential of a sufficient voltage to send enough current through the filament to cause it to come to a dull red glow. He then applies heat to the neck of the lamp bulb, inserts the jaws of the pliers into the stem 32, as hereinbefore described, and 15 bends the neck of the bulb until the filament occupies the desired position with respect to its reflex image. If for instance, it is desired to locate the filament centrally in the lamp bulb, the operator adjusts the filament until 20 the reflex image coincides in position with the filament, as shown in Fig. 13. It is apparent that this is a very expedient method for securing adjustment of the filament with respect to the bulb and is of special advantage where it is desired to locate the filament 25 in the center of the lamp bulb, although it is possible to secure an accurate location of the filament above or below the center of the bulb by adjusting the filament so that the image is at a given distance above or below 30 the reflex image.

Although I have herein shown and described only a few forms of apparatus embodying my invention, and have explained only a few methods embodying my invention, it is understood that various changes and modifications may be made therein within the scope of the appended claims 45 without departing from the spirit and scope 50 of my invention.

Having thus described my invention, what I claim is:

1. The method of adjusting commercial incandescent electric lamps which consists in heating to a plastic state the portion of the bulb to which the filament is attached whereby the filament may be moved with respect to the bulb, and locating the filament by optical means at a predetermined position with respect to the surface of the bulb.

2. The method of adjusting commercial incandescent lamps which consists in determining the desired position of the filament with respect to the bulb surface, heating to 65 a plastic state the portion of the bulb to

which the filament is attached, and then moving the filament to such predetermined position.

3. The method of adjusting commercial incandescent lamps which consists in determining by optical means the desired position of the filament with respect to the bulb surface, heating to a plastic state the portion of the bulb to which the filament is attached, and then moving the filament to such predetermined position.

4. The method of adjusting commercial incandescent electric lamps which consists in applying heat to render the filament movable with respect to the bulb, and moving the filament to a predetermined position with respect to the bulb surface.

5. The method of adjusting incandescent electric lamps, which consists in heating to a plastic state the portion of the lamp bulb to which is attached the stem carrying the filament, whereby the stem may be moved with respect to the bulb, and moving the stem until the filament occupies a predetermined position with respect to the bulb.

6. Apparatus for adjusting commercial incandescent electric lamps, comprising means for rendering the lamp filament movable with respect to the lamp bulb, and means for determining when the filament occupies a predetermined position with respect to the surface of the bulb.

7. In combination, a base member, means for mounting a lamp bulb thereon in a given position, means for applying heat to said bulb to render the same plastic whereby the filament may be moved with respect to the bulb, and optical means carried by said base member for determining when the filament occupies a predetermined position with respect to said base member.

8. In combination, a base member, means for mounting a commercial incandescent electric lamp thereon so that the bulb surface occupies a predetermined position with respect to said member, means for rendering plastic the portion of the bulb to which the filament is attached whereby the filament may be moved with respect to the bulb, and optical means for determining when the filament occupies a predetermined position with respect to said base member.

9. In combination, a base member, optical means for determining a fixed point with relation to said member, means for holding a lamp bulb to said member in a predetermined position with relation to said point, and means for heating to a plastic state the portion of said bulb to which the filament is attached whereby the filament may be moved to said point.

10. In combination, means for holding an incandescent lamp bulb, and a rotary gas jet for heating to a plastic state the portion of said bulb to which the filament is at-

tached, whereby the filament may be adjusted with respect to the bulb.

11. In combination, optical means for projecting a beam of light, an incandescent lamp having the filament accurately located at a given point with respect to a portion of the surface of the bulb, and means for mounting said electric lamp so that the said portion of the bulb surface occupies a predetermined position with respect to the said optical means.

12. In combination, a lens, an incandescent lamp having the filament accurately located at a given point with respect to a portion of the bulb surface, and means for mounting said lamp so that the said portion of the bulb surface occupies a predetermined position with respect to said lens.

13. The process of locating the filament of an incandescent lamp with respect to the bulb surface which comprises heating the end of the bulb which supports the filament, determining by optical means the proper location for said filament, bending the heated

surface of the bulb so that said filament is 25 brought into said proper location, and cooling the heated surface.

14. In combination, means for holding an incandescent lamp bulb, a rotary gas jet for heating to a plastic state the portion of said 30 bulb to which the filament is attached whereby the filament may be moved with respect to the bulb, and optical means for determining when the filament occupies a predetermined position with respect to the bulb. 35

15. The method of locating the filament of an incandescent lamp accurately with respect to an optical device, which consists in accurately locating the filament with respect to a portion of the bulb surface and accurately 40 locating said portion of the bulb surface with respect to said optical device.

In testimony whereof I affix my signature in presence of two witnesses.

CLARENCE S. SNAVELY.
